THERMIONIC VACUUM TUBE CIRCUIT FOR
INTERCOMMUNICATION SYSTEMS

Sol J. Klapman, Chicago, Ill.

Application January 11, 1947, Serial No. 721,589

17 Claims. (Cl. 179—37)

1

This invention relates generally to amplifiers and has particular reference to the application of such amplifiers to inter-office communication systems.

In communication systems employing vacuum tubes as a means of amplifying voice currents it has been the practice to employ circuits which require that the filaments of the vacuum tubes used therein to be heated even during periods of no operation. Since the useful life of the tubes employed is proportional to the period when the filaments are heated, such systems are open to the objection that the useful portion of the life of the tubes used therein is only a small fraction of the possible total life of the tubes.

In order to attain a large amount of useful tube life as compared to the total available tube life it has been the practice to have the filaments heated only when the system is in use, that is, when actually used for communication between two or more stations. However, in such operation, it takes an inordinately long time for the filaments to become heated and the system to become ready for operation, and the advantages accruing from long life of the tubes in the system do not compensate for the delay or wait necessary for the system to be ready and operable.

With the foregoing considerations in mind it is an object of the present invention to provide a communication system which will be practically instantaneously available for operation, and which will not require the consumption of power by vacuum tubes used therein, except when they are being used in amplifying voice currents, to the end the tubes employed in the system will have a very long useful life as compared to the total life of the tubes.

A further object is to provide a novel circuit for a communication system which will create no power demand during periods when the system is not in actual use, but which will provide for practically immediate operation when the system is called into use.

A yet further object comprehends a circuit for a communication system which will store a quantity of electrical energy which will make the system immediately available for operation.

Still another object is to provide in such a communication system a circuit which operates as a filter against noises from an alternating current source and which will absorb a portion of the energy stored in the circuit when the system is called into operation.

2

Another object is to provide a circuit for a communication system, the circuit having means associated therewith for storing energy for instantly heating the tubes, the means thereafter being inactive and the tubes thereafter being heated in the normal manner.

Still another object of the invention comprehends the provision of an amplifier for each station of an intercommunication system, a single transducer being provided at each station for use alternately as a microphone and a loudspeaker, the transducer being connected to the input of the station amplifier in talking, and to the output of a remote station in listening.

15 Other objects of the invention will be apparent from a study of the description hereinafter taken together with the drawings in which the single figure shows a schematic diagram of a five station intercommunication system, two of the stations being shown in detail.

20 Referring now to the drawing, there is shown Station A and Station B of a five station intercommunication system. Each station has as a part thereof a two stage amplifier consisting of a first stage of amplification, indicated generally by the ordinal 10, and a second stage of amplification, indicated generally by the ordinal 12. Power is supplied for the amplification stages 10 and 12 from an alternating current source 14, which is connected through an overload fuse 16 to a selenium rectifier 18 which provides a potential high enough to supply anode voltage.

25 The rectifier 18 is connected by a lead 20 to a filter network consisting of a resistor 22 and capacitors 24 and 26 where the voltage derived at the rectifier 18 is suitably filtered.

30 Stations A and B, as are all the stations of the system, are each provided with a talk-listen switch, indicated by the ordinal 28, which is of the three-pole, double-throw type, the switch 28 being normally closed in the listen position as shown. In the other or talk position voltage is supplied by the rectifier 18 through an indicator lamp 30 and a dropping resistor 32, 35 through conductors 34 and 36 to cathodes 38 and 40 of amplification stages 10 and 12, a dropping resistor 42 between the cathodes 38 and 40 being provided to maintain the proper voltages thereacross.

40 The supply to the cathodes 38 and 40 is suitably filtered by means of capacitors 44, 46, and 48, capacitors 48 being of a large enough capacity for additional functions as will appear later.

45 50 The arrangement thus far described provides

suitable cathode, anode and grid voltages to a two stage amplifier, which under ordinary conditions would be available for operation within the usual warm-up period. However, as has been pointed out above, the normal time of warm-up is much too long for efficient use of an intercommunication system, and accordingly means are provided which will heat the tubes of amplifier stages 10 and 12 almost instantaneously, the tubes thereafter being ready for normal use. To this end, the rectifier 18 is connected to a capacitor 50, which when the switch 28 is in the listen position, will be charged at the voltage derived at the rectifier 18, this voltage being the same as the anode voltage derived for the amplification stages 10 and 12. When the switch 28 is moved to the talk position the charge stored in the capacitor 50 is released through the leads 34 and 36 to the cathode circuit comprising cathodes 38 and 40, the dropping resistor 42 and the filter network comprising capacitors 44, 46, and 48. The initial surge of current arising from the discharge of the capacitor 50 is largely absorbed by the capacitor 48, which, is of a capacity larger than that required for ordinary filtering. Capacitor 48 must be of sufficient capacity to reduce the shock on the cathode 40 to well below the damage point, but must also be of low enough capacity that not too great a time interval is required in charging, which would result in too great a time lag before the system would be operative. The remaining surge of current arising from the discharge of the capacitor 50 then serves to heat the cathodes 38 and 40 very quickly, thus making the amplification stages 10 and 12 in a condition for almost instantaneous operation. Thereafter, with the switch 28 in the talk position voltage is supplied to the cathode circuit through the indicator lamp 30, the dropping resistor 32 and the leads 34 and 36. It will be apparent that the operator is apprised of the "ready" condition of the system as soon as the indicator lamp 30 is illuminated.

In the system shown, each station is provided with a transducer 52, which operates as a microphone with the switch 28 in the talk position, and as a loud speaker with the switch 28 in the listen position, which is connected through the talk-listen switch 28 to a conductor 54 to the primary of an input transformer 56, the secondary of which is connected to a grid 58 of tube 10. The output from tube 10 is capacity coupled to an input grid 62 of the second stage of amplification 12 through a volume control 64. The output from amplification stage 12 is connected by conductor 66 to the primary winding of an output transformer 68, the secondary of which is connected to conductor 70 through the switch 28, and thence to a conductor 72 of a station selector indicated generally by the ordinal 74.

As shown, the station selector 74 is set for talking to Station B, and is connected by conductor 76 which connects to a conductor 78 of a cable connecting the five stations of the system and common to each of the stations of the system. Station B is in the listen position and the conductor 78 is connected to the talk-listen switch 28 of Station B, and the amplified voice currents of Station A directly energize the transducer 52 of Station B. Station B is connected at its associated station selector for talk to Station A. When it is desired that Station B talk to Station A the operator has merely to move the talk-listen switch 28 of Station B to the talk

position. It will be seen that regardless of the position of the selector switch 74 of Station A that communication will be had with that station alone. At such time as the talk-listen switch 28 of Station B is moved to the talk position the amplifier of Station B will be instantaneously available for amplifying voice currents developed in the transducer 52 of Station B and deliver the so amplified voice currents to the transducer of Station A.

It will be apparent from the foregoing description that there has been provided an intercommunication system which is extremely efficient from the standpoint of tube life, and which is always instantaneously operable. While the invention has been described in terms of a preferred embodiment thereof, its scope is not limited in terms of the embodiment shown, nor otherwise than by the claims here appended.

20 I claim:

1. An amplifier for an intercommunication system comprising a plurality of thermionic tubes; anode, cathode, and grid electrodes for each of said thermionic tubes; a power source; means connected to said power source for supplying voltage at said anode and grid electrodes; a filter system in circuit with said cathode electrodes; a capacitor charged at the anode supply voltage when said tubes are in a non-emitting condition; and switch means for connecting said capacitor in circuit with said cathode electrodes for rapidly heating said cathode electrodes upon the discharge of said capacitor.

2. An amplifier for an intercommunication system comprising a plurality of thermionic tubes; anode, cathode, and grid electrodes for each of said thermionic tubes; a power source; means connected to said power source for supplying voltage at said anode and grid electrodes; a circuit for said cathode electrodes including capacitors therein for filtering undesirable voltages from said circuit; a capacitor charged at the anode supply voltage when said tubes are in a non-emitting condition; and switch means for connecting said capacitor in circuit with said cathode electrodes for rapidly heating said cathode electrodes upon the discharge of said capacitor, the discharge of said capacitor being subsequent to the application of the voltage at said anode and said grid electrodes by the said first means.

3. An amplifier for an intercommunication system comprising a plurality of thermionic tubes; anode, cathode, and grid electrodes for each of said thermionic tubes; a power source; means connected to said power source for supplying voltage at said anode and grid electrodes; a circuit for said cathode electrodes including capacitors therein for filtering undesirable voltages from said circuit; a capacitor charged at the anode supply voltage when said tubes are in a non-emitting condition; and switch means for connecting said capacitor in circuit with said cathode electrodes for rapidly heating said cathode electrodes upon the discharge of said capacitor, the discharge of said capacitor being subsequent to the application of the voltage at said anode and said grid electrodes by the said first means.

4. An amplifier for an intercommunication system comprising a plurality of thermionic tubes; anode, cathode, and grid electrodes for each of said thermionic tubes; a power source; means connected to said power source for supplying voltage at said anode and grid electrodes; a circuit for said cathode electrodes including

capacitors therein for filtering undesirable voltages from said circuit; a capacitor charged at the anode supply voltage when said tubes are in a non-emitting condition; and switch means for connecting said last named capacitor in circuit with said cathode electrodes for rapidly heating said cathode electrodes; said circuit for said cathode electrodes having at least one capacitor therein for taking a portion of the surge current caused by operation of said switch means; said cathode circuit being thereafter supplied from said power source.

5. An amplifier for an intercommunication system comprising a plurality of thermionic tubes; anode, cathode and grid electrodes for each of said thermionic tubes; a power source; means for rectifying current from said power source; a circuit including said means for supplying anode and grid voltages; a circuit including said cathodes having capacitors therein for filtering undesired voltages therefrom; a capacitor charged at the anode supply voltage when said tubes are in a non-emitting condition; and switch means for connecting said capacitor in circuit with said cathode electrodes for rapidly heating said cathode electrodes upon the discharge of said capacitor.

6. An amplifier for an intercommunication system comprising a plurality of thermionic tubes; anode, cathode and grid electrodes for each of said thermionic tubes; a power source; means for rectifying current from said power source; a circuit including said means for supplying anode and grid voltages; a circuit including said cathodes having capacitors therein for filtering undesired voltages therefrom; a capacitor charged at the anode supply voltage when said tubes are in a non-emitting condition; and switch means for connecting said capacitor in circuit with said cathode electrodes; said circuit for said cathode electrodes having at least one capacitor therein for taking a portion of the surge current caused by operation of said switch means.

7. An amplifier for an intercommunication system comprising a plurality of thermionic tubes; anode, cathode and grid electrodes for each of said thermionic tubes; a power source; means for rectifying current from said power source; a circuit including said means for supplying anode and grid voltages; a circuit including said cathodes having capacitors therein for filtering undesired voltages therefrom; a capacitor charged at the anode supply voltage when said tubes are in a non-emitting condition; and switch means for connecting said last named capacitor in circuit with said cathode electrodes; said circuit for said cathode electrodes having at least one capacitor therein for taking a portion of the surge current caused by operation of said switch means and the discharge of said last named capacitor; said cathode circuit being thereafter supplied from said rectifying means.

8. In an intercommunication system of the type having a plurality of stations; each station being provided with an amplifier and a transducer capable of being connected to the input of its associated amplifier; said transducer being also capable of being connected to the output of an amplifier of a remote station; said amplifier comprising at least one thermionic tube; anode, cathode and grid electrodes for said thermionic tube; a power source; means for rectifying current from said power source; a circuit including said means for supplying anode and grid voltages; a circuit including said cathode electrode having

capacitors therein for filtering undesired voltages therefrom; a capacitor charged at the anode supply voltage when said tubes are in a non-emitting condition; and switch means for connecting said last named capacitor in circuit with said cathode electrode for rapidly heating said cathode electrode upon the discharge of said last named capacitor.

9. An amplifier for an intercommunication system comprising a plurality of thermionic tubes; anode, cathode and grid electrodes for each of said thermionic tubes; a power source; means for rectifying current from said power source; a circuit including said means for supplying anode and grid voltages; a circuit including said cathodes having capacitors therein for filtering undesired voltages therefrom; a capacitor charged at the anode supply voltage when said tubes are in a non-emitting condition; and switch means for connecting said last named capacitor in circuit with said cathode electrodes; said circuit for said cathode electrodes having at least one capacitor therein for taking a portion of the surge current caused by operation of said switch means; said last named capacitor in said cathode electrode circuit being of sufficient capacity to eliminate the shock on one of cathodes and of a sufficiently small capacity to maintain the period of charge thereon at a minimum consistent with maintaining the surge against said cathode below the damage point.

10. In an intercommunication system of the type having a plurality of stations; each station being provided with an amplifier and a transducer capable of being connected to the input of its associated amplifier; said transducer being also capable of being connected to the output of an amplifier of a remote station; said amplifier comprising a plurality of thermionic tubes; anode, cathode and grid electrodes for each of said thermionic tubes; a power source; means for rectifying current from said power source; a circuit including said means for supplying anode and grid voltages; a circuit including said cathodes having capacitors therein for filtering undesired voltages therefrom; a capacitor charged at the anode supply voltage when said tubes are in a non-emitting condition; and switch means for connecting said capacitor in circuit with said cathode electrodes for rapidly heating said cathode electrodes upon the discharge of said capacitor; said circuit for said cathode electrodes having at least one capacitor therein for taking a portion of the surge current caused by operation of said switch means.

11. In an intercommunication system of the type having a plurality of stations; each station being provided with an amplifier and a transducer capable of being connected to the input of its associated amplifier; said transducer being also capable of being connected to the output of an amplifier of a remote station; said amplifier comprising at least one thermionic tube; anode, cathode and grid electrodes for said thermionic tube; a power source; means for rectifying current from said power source; a circuit including said means for supplying anode and grid voltages; a circuit including said cathode electrode having capacitors therein for filtering undesired voltages therefrom; a capacitor charged at the anode supply voltage when said tubes are in a non-emitting condition; and switch means for connecting said capacitor in circuit with said cathode electrodes for rapidly heating said cath-

ode electrodes upon the discharge of said capacitor; said circuit for said cathode electrode having at least one capacitor therein for taking a substantial portion of the surge current caused by operation of said switch means, said cathode circuit being thereafter supplied from said rectifying means.

12. In an intercommunication system of the type having a plurality of stations; each station being provided with an amplifier and a transducer capable of being connected to the input of its associated amplifier; said transducer being also capable of being connected to the output of an amplifier of a remote station; said amplifier comprising a plurality of thermionic tubes having anode, cathode and grid electrodes; a power source, means for rectifying current from said power source; a circuit including said last named means for supplying anode and grid voltages; a circuit including said cathode electrodes having capacitors therein for filtering undesired voltages therefrom; a capacitor charged at the anode voltage when said tubes are in a non-emitting condition; switch means normally connecting the transducer of an adjacent station to the output of a remote station; said switch means being operable to connect the output of its associated station to the transducer of a remote station; said switch means being also operable to connect said last named capacitor in circuit with said cathode electrodes for rapidly heating said cathode electrodes upon the discharge of said last named capacitor.

13. In an intercommunication system of the type having a plurality of stations; each station being provided with an amplifier and a transducer capable of being connected to the input of its associated amplifier; said transducer being also capable of being connected to the output of an amplifier of a remote station; said amplifier comprising a plurality of thermionic tubes having anode, cathode and grid electrodes; a power source; means for rectifying current from said power source; a circuit including said last named means for supplying anode and grid voltages; a circuit including said cathodes having capacitors therein for filtering undesired voltages therefrom; a capacitor charged at the anode supply voltage when said tubes are in a non-emitting condition; switch means normally connecting the transducer of an adjacent station to the output of a remote station; said switch means being operable to connect the output of its associated station to the transducer of a remote station; said switch means being also operable to connect said last named capacitor in circuit with said cathode electrodes for rapidly heating said cathode electrodes upon the discharge of said last named capacitor; the cathode electrode circuit having at least one capacitor therein for taking a portion of the surge current caused by the operation of said switch means.

14. In an intercommunication system of the type having a plurality of stations; each station being provided with an amplifier and a transducer capable of being connected to the input of its associated amplifier; said transducer being also capable of being connected to the output of an amplifier of a remote station; said amplifier comprising a plurality of thermionic tubes having anode, cathode and grid electrodes; a power

source, means for rectifying current from said power source; a circuit including said last named means for supplying anode and grid voltages; a circuit including said cathode electrodes having capacitors therein for filtering undesired voltages therefrom; a capacitor charged at the anode supply voltage when said tubes are in a non-emitting condition; switch means normally connecting the transducer of an adjacent station to the output of a remote station; said switch means being operable to connect the output of its associated station to the transducer of a remote station; said switch means being also operable to connect said last named capacitor in circuit with said cathode electrodes for rapidly heating said cathode electrodes upon the discharge of said last named capacitor; the cathode electrode circuit having a capacitor therein of sufficient capacity to reduce the shock on said cathode electrodes and of sufficiently small capacity to maintain the period of charge thereon at a minimum consistent with maintaining the surge against said cathodes below the damage point.

15. In an intercommunication system of the type having a plurality of stations; each station being provided with an amplifier and a transducer capable of being connected to the input of its associated amplifier; said transducer being also capable of being connected to the output of an amplifier of a remote station; said amplifier comprising a plurality of thermionic tubes having anode, cathode and grid electrodes; a power source; means for rectifying current from said power source; a circuit including said last named means for supplying anode and grid voltages; a circuit including said cathodes having capacitors therein for filtering undesired voltages therefrom; a capacitor charged at the anode supply voltage when said tubes are in a non-emitting condition; switch means normally connecting said transducer to the output of a remote station; said switch means being operable to connect the output of its associated station to the transducer of a remote station, said switch means being also operable to connect said last named capacitor in circuit with said cathode electrodes for rapidly heating said cathode electrodes upon the discharge of said last named capacitor; said circuit having at least one capacitor of sufficient capacity therein for taking a portion of the surge current caused by the operation of said switch means; said cathode circuit being thereafter supplied from said rectifying means.

16. The invention as defined in claim 13 wherein means are provided for indicating the operability of said amplifier immediately after the operation of said switch means.

17. The invention as defined in claim 15 wherein means are provided for indicating the operability of said amplifier immediately after the operation of said switch means.
